UNITED STATES PATENT OFFICE.

STEFAN WOJCIK, OF DETROIT, MICHIGAN, ASSIGNOR OF ONE-HALF TO JACOB LEWANDOWSKI, OF DETROIT, MICHIGAN.

SASH-FASTENER.

1,397,668.

Specification of Letters Patent.

Patented Nov. 22, 1921.

Application filed November 30, 1920. Serial No. 427,435.

To all whom it may concern:

Be it known that I, STEFAN WOJCIK, a citizen of Poland, residing at Detroit, in the county of Wayne and State of Michigan, have invented certain new and useful Improvements in Sash-Fasteners, of which the following is a specification.

This invention relates to certain new and useful improvements in sash fasteners and has particular reference to a fastener supported on a window casing and carrying tensioned bolts for engagement with upper and lower window sashes to hold the same in closed locked positions.

15 A further object of the invention resides in the provision of a sash fastener supported on a window frame and carrying a pair of independently operable tensioned bolts adapted for reception in sockets provided in 20 the adjacent edges of the upper and lower window sashes to hold the sashes either in closed locked position or in various open immovable positions, thus permitting the window to be partially opened and so retained 25 against unauthorized movements.

With the above general objects in view and others that will become apparent as the nature of the invention is better understood, the same consists in the novel form, combination and arrangement of parts hereinafter 30 more fully described, shown in the accompanying drawings and claimed.

In the drawings, wherein like reference characters indicate corresponding parts 35 throughout the several views,

Figure 1 is a fragmentary horizontal sectional view through a portion of a window frame showing a latch casing supported thereon with projecting bolts holding the 40 upper and lower sashes immovable,

Fig. 2 is a fragmentary side elevational view of a portion of the window frame showing the locking bolts for the sashes projecting from the frame,

45 Fig. 3 is a fragmentary front elevational view of the window frame showing the plunger heads for shifting the locking bolts,

Fig. 4 is a detail sectional view showing the latch casing supported on the window frame with the tensioned bolts carried there- 50 by extending into sockets formed in the edges of the upper and lower window sashes,

Fig. 5 is a fragmentary side elevational view of the upper and lower sashes with 55 apertured face plates secured thereto,

Fig. 6 is a detail sectional view of the latch casing showing the tensioned sash engaging bolts and one of the plunger rods for shifting one of the bolts.

Fig. 7 is a perspective view of one of the 60 sash base plates, and

Fig. 8 is a fragmentary perspective view of the locking bolt and a portion of the operating mechanism therefor.

Referring more in detail to the accompanying drawings there is illustrated a sash fastener construction associated with a window frame 1 supported in the wall 2, the frame 1 including a side wall 3 with the adjacent edges of upper and lower sashes 4 and 5 slidably associated therewith and separated by the parting strip 6 with the forward molding 7 holding the lower sash 4 in position. As shown in Fig. 5 the lower and upper sashes 4 and 5 have meeting 75 rails 8 adapted for engagement when the sashes are in their closed positions.

The edges of the sashes 4 and 5 adjacent the side wall 3 of the window frame are slightly cut away for the counter-sunk face 80 plates 9 secured thereto by fastening devices 10 and having vertically aligned openings 11 formed therein with overlying flanges 12, the openings 11 in the face plates 9 registering with sockets 13 in the edges of 85 the window sashes 4 and 5, into which openings sliding latch bolts are adapted to be projected to hold the windows in operative closed locked positions or partially open.

A latch casing 14 is disposed within the 90 hollow window frame 1 and is secured to the side wall 3 of the frame by the fastening device 15. A pair of tensioned bolts 16 having tapered nose ends 17 projecting through the side of the casing 14 and 95 through openings 18 in the frame wall 3 and through the openings 11 in the face plates 9 for projection into the sockets 13 in the window sashes. The detail latch construction is shown more clearly in Figs. 4, 100 6 and 8, a vertical pin 19 supported in the walls of the casing 14 having the coiled portions 20 of spring arms 21 and 22 projecting therefrom, the spring arms 21 engaging the adjacent side walls of the casing 14 while the spring arms 22 are positioned for engagement with the pintles 23 carried by the bolts 16 normally to hold the bolts spring pressed outwardly of the 105 casing for reception in the sash sockets 13. 110

To retract the tension bolts from engagement with the window sashes 4 and 5, a bell crank is associated with each bolt 16, the bell crank being pivotally mounted within the casing as at 24 and having the end of the leg 25 bifurcated as at 26 for inclosing the pins 27 projecting from the bolt 16, the other leg 28 having an operating rod 29 attached thereto with a press button 30 upon the outer end whereof, the two rods 29 of the operating devices for the two bolts 16 slidably projecting through the front wall of the window frame 1 with the push button positioned exteriorly of the window frame as shown in Figs. 1 and 2 while a face plate 31 carried by the outer face of the window frame provides a sliding guide for the push buttons.

From an inspection of Fig. 2 it will be noted that the tensioned bolts 16 are laterally disposed for engagement with the upper and lower sashes respectively. When it is desired to release either of the window sashes, the desired push button 30 is operated to cause the rod 29 to move the bell crank and retract the bolt 16 through the casing against the tension of the adjacent spring arm 22 to remove the tapered end 17 of the bolt from the socket 13 in the window sash 30 and the opening 11 in the sash plate 9.

By the provision of this device, the window sashes may either be locked in closed positions or partially opened and so retained against unauthorized movements.

While there is herein shown and described the preferred embodiment of the present invention, it is nevertheless to be understood that minor changes may be made therein without departing from the spirit and scope of the invention as claimed.

What is claimed as new is:—

A sash fastener of the type described comprising in combination with window sashes provided with vertically aligned sockets therein, a latch casing, a pair of sliding bolts mounted therein, a pin extending transversely of the casing between the bolts, a pair of independently operable spring arms supported on said pin and engaging at their ends one side wall of the casing and said bolts to normally hold the bolts projected into sash sockets, a bell crank pivotally mounted within the casing for each bolt and having a loose connection therewith, and independently operable devices for operating the bell cranks to shift the bolts against the tension thereon to remove the same from the sash sockets.

In testimony whereof I affix my signature.
STEFAN WOJCIK.
